DESIGN FOR A FINGER RING

Frank Klein, Oradell, N. J.

Application July 16, 1943, Serial No. 110,673

Term of patent 7 years

To all whom it may concern:

Be it known that I, Frank Klein, a citizen of the United States, residing in the Borough of Oradell, county of Bergen, and State of New Jersey, have invented a new, original, and ornamental Design for a Finger Ring, of which the following is a specification, reference being had to the accompanying drawing, forming a part thereof.

In the drawing, Fig. 1 is a perspective view of a finger ring embodying my design, Fig. 2 is a perspective view thereof, taken on line 2—2 of Fig. 1, in the direction of the arrows, and Fig. 3 is a perspective view thereof taken on line 3—3 of Fig. 1, in the direction of the arrows.

The characteristic features of my design are shown in full lines in the drawing.

I claim:

The ornamental design for a finger ring, as shown and described.

FRANK KLEIN,
